UNITED STATES PATENT OFFICE.

MALCOLM CURRY, OF SCARSDALE, NEW YORK, AND STARR H. BARNUM, OF HAMDEN, CONNECTICUT.

OBSERVATION WINDOW FOR FURNACES.

Application filed May 14, 1926. Serial No. 109,093.

This invention relates to improvements in observation windows for furnaces and the like, and has for one of its objects to provide windows of simple and inexpensive construction through which the fuel bed may be clearly seen without the observer being subjected to the direct heat and glare of the fire-box and without opening communication between the fire-box and the outer atmosphere.

10 A further object of the invention is to provide simple and efficient means for preventing the transparent glare-eliminating panel of the window from becoming unduly heated during inspection of the fuel bed.

Another important object of the invention is to provide a woven wire heat-absorbing sheet located between the glare-eliminating panel and the opening into the furnace, 20 and so arranging said heat-absorbing sheet as to subject it to cooling air currents exterior of the furnace.

Another object of the invention is to provide a glare-eliminating panel formed of a 25 gelatin sheet confined between woven wire gauze sheets, the gelatin sheet being preferably blue in color and the wire gauze serving as means to hold the sheet flat and also as a heat-absorbing and diffusing means.

30 Another object of the invention is to provide means for removably and resiliently holding the woven wire heat-absorbing sheet in position in the frame of the observation window.

35 To the foregoing and other ends, which will hereinafter appear, the invention consists in the features of construction, arrangements of parts, and combinations of devices set forth in the following description and 40 particularly pointed out in the appended claims.

In the drawings:

Fig. 1 is a front elevation of the window;

45 Fig. 2 a vertical sectional view taken on the line 2-2 of Fig. 1 showing the sliding frame in its normal lowered position;

Fig. 3 a horizontal sectional view taken on the line 3-3 of Fig. 2 showing the sliding frame raised and the window open for observation;

Fig. 4 a detail perspective view of the woven wire heat-absorbing sheet;

Fig. 5 a detail perspective view of the glare-eliminating panel;

55 Fig. 6 a detail sectional view showing a

glass plate in position as a glare-eliminating panel;

Fig. 7 a detail perspective view of a modified form of means for resiliently holding the heat-absorbing sheet in position in the frame of the window; and

Fig. 8 a detail perspective view of a portion of a modified form of a glare-eliminating panel.

The furnace wall 10, which may be of any suitable construction, is provided with a peep-opening 11 at a point suitable for observing the fuel bed. This opening may be of any suitable shape in cross section, but preferably the side walls flare inwardly and 70 the lower wall inclines inwardly and downwardly to enable the observer to view the fuel bed. While we prefer to provide the peep-opening in the brick wall of the furnace, as shown, it will be obvious that the 75 opening may be formed in any suitable part of the furnace, and that the window herein-after described may be attached to furnace walls, casings, or doors of various construction provided with peep-openings. 80

The metallic window frame or casing 12 is constructed substantially as shown in our Patent No. 1,417,976, dated May 30, 1922. It is of general rectangular box-like form, is preferably cast in one piece, as shown, said 85 frame being formed with a bolt flange 13 around its open inner end and being held against the outer side of the furnace wall over the peep-opening by bolts. The top, bottom and side edges of the frame are preferably offset from the corresponding edges of the peep-opening, as shown, so that the brick wall will be interposed between the edges of the frame and the combustion chamber of the furnace to afford protection to the 95 frame.

The outer end wall of the frame 12 is provided with a rectangular view opening 16 registering with the peep-opening 11, and is formed with integral upturned lugs 17 along 100 the lower edge of opening 16 and integral inwardly turned lugs 18 along the vertical edges of openings 16, said lugs 17 and 18 forming retaining means for a plate 19 of blue or other suitably colored glare-eliminating transparent material. This plate may be a sheet of blue gelatin or other non-frangible material held firmly between two sheets of fine wire gauze 20. The gauze sheets are pressed firmly together and serve to hold 110

the gelatin sheet flat and to form a plate sufficiently rigid to permit it to be readily placed in position on the lugs 17 of the frame. The wire gauze-enclosing means is 5 preferably formed of a single sheet of gauze overlapped around one edge of the gelatin sheet as shown in Fig. 5. This is a convenient and cheap means of forming the glare-eliminating panel. The gauze sheets serve 10 as heat-absorbing and diffusing means. When the panel is in position on the frame the wire gauze is in intimate contact with the metal of the frame and the heat absorbed by the gauze will be readily transmitted to 15 the metal frame. It will, of course, be understood that instead of using the gelatin and gauze panel, a sheet of blue glass 19^a may be substituted therefor, as shown in Fig. 6.

20 A supplemental metal frame, preferably cast in one piece, is slidable through the main frame or casing 12. The slidable frame comprises side bars 21 loosely fitting in guideways or channels 22 formed in the im- 25 perforate side walls of the frame 12, a top cross-bar 23, a bottom-cross-bar 24, and an intermediate cross-bar 25. Said sliding frame is normally held by gravity in the position shown in Figs. 1 and 2, in which position its downward movement is arrested by 30 the engagement of a flange 26, formed around the upper edge of the cross-bar 23, with the top wall of the frame 12. The top wall of the outer frame or casing 12 is 35 formed with a rectangular slot 27, through which the supplemental frame is slidable, and the bottom wall is formed with a flange 28 on which the intermediate cross-bar seats when the parts are in the position shown in 40 Figs. 1 and 2. The bottom wall of the cas- 45 ing 12 is provided with a slot 29 to permit movement of the side bars 21 and bottom cross-bar 24 therethrough. The top cross- 50 bar 23 is provided with a longitudinal slot 30 through which one or more panels or plates 31 of opaque non-combustible material which is also a non-conductor of heat, such as asbestos boards, are inserted in the upper section of the sliding frame, said asbestos 55 plates 31 resting on bar 25 and being held in the frame by suitable means. One of the side bars 21 of the sliding frame is provided with a vertical slot 33, extending between cross-bars 24 and 25, through which a sheet 60 or plate 34 of transparent non-combustible or heat-resisting material, such as mica, is slidably inserted in the lower half of the frame. The mica sheet 34 is retained in the sliding frame by pairs of lugs 35 formed on bars 21, 24 and 25. A suitable handle 37 is secured to the lower cross-bar 24 of the sliding frame.

65 It will be observed that when the parts are in the position shown in Figs. 1 and 2, bars 25 and 23 close slots 29 and 27 so that there

can be no substantial influx of air, while the asbestos boards 31 prevent inward or outward passage of air through the sliding frame and shield the glare-eliminating panel 19 from heat radiating through the peep-opening 11 and also from flame, hot gases and soot. When the sliding frame is raised by pushing up on handle 37, the asbestos boards are moved out of register with the peep-opening and the sheet of mica is moved 70 between the peep-opening and the blue panel to shield the panel and permit observation of the fuel bed. When the parts are in raised position it will be observed that the mica sheet and cross-bars 24 and 25 will prevent 75 the influx of cold air through the peep-opening, the bar 25 closing slot 27 and bar 24 closing communication through the slot 29 and the peep-opening 11. The handle 37 engages the bottom wall of casing 12 to 80 arrest the sliding frame in the position shown in dotted lines in Fig. 2.

85 The window frame is formed with hori- 90 zontally extending grooved guideways 38, said guideways being formed on the upper and lower walls of the frame and the guide 95 grooves being formed along the inner surface thereof. These guideways are formed substantially midway between the sliding frame and the view opening 16 in the front 100 wall of the casing 12. In the upper and lower walls of the casing 12, on opposite sides of the guideways 38 are formed open- 105 ings 39 so that air may pass upwardly through the casing 12 along both sides of the grooved ways and along the inner side 110 of the glare-eliminating panel 19. One vertical wall of the casing 12 is formed with a vertical slot 40 which opens into the grooves of the guideways 38. Fitting the guideways, 115 and removable through the slot 40, is a woven wire heat-absorbing-and-diverting sheet 41. This heat-absorbing sheet is pref- 120 erably formed of a comparatively fine mesh of woven wire, but it must be of a sufficiently 125 large mesh to permit the fire or fuel bed to be viewed through it. The heat-absorbing sheet is resiliently pressed against the walls of the grooved guideways by spring flanges 130 135 42 formed integral with the longitudinally extending binding flanges 43. These binding flanges are clamped along the upper and lower longitudinal edges of the gauze sheet, as shown clearly in Fig. 4. The spring flanges 42 press the binding flanges 43 into 140 intimate contact with the metal of the frame. The spring flanges 42 also bear on the walls of the grooved guideways and furnish ad- 145 ditional metallic contact between the heat-absorbing wire gauze and the metal of the casing 12. The vertical flange of the casing 12, opposite the slot 40 is formed with in- 150 wardly extending flanges 44 to receive be- 155 tween them the inner vertical edge of the sheet 41. That end of the sheet 41 which 160

rests within the slot 40, is provided with an outwardly extending tab or finger piece 45 by means of which the sheet may be readily drawn from the casing for cleaning and 5 inserted therein. The finger piece 45 is preferably formed integral with a metallic binding strip 46 which is clamped along the edge of the sheet 41.

If desired the spring flanges 42 may be 10 omitted and the sheet 41 resiliently held in place by means of spring strips 47 or similar resilient means which may be inserted in the grooved guideways 38 and serve as means for pressing the upper and lower edges of the 15 heat-absorbing sheet 41 into intimate contact with the metal of the casing 12.

When the sliding frame is raised the mica sheet 34 is interposed between the peep-opening 11 and the heat-absorbing wire 20 gauze sheet 41. The heat passing through 25 the mica will be largely absorbed by the wire gauze and transmitted to the casing 12. There will be a rapid circulation of outside air up through the openings 39 on opposite 30 sides of the gauze sheet, said circulation serving to cool the wire gauze and the casing 12. The gelatin sheet is protected by its enclosing sheets of wire gauze. These wire gauze sheets will also serve to absorb heat and 35 transmit it to the casing 12. These wire gauze sheets of the glare-eliminating panel will also be cooled by the upward currents of air flowing through the casing and outside of it. The wire gauze enclosing sheets and 40 the blue gelatin sheet form a non-breakable glare-eliminating panel. The gelatin is sufficiently protected from the furnace heat by the woven wire sheets and by the outside air currents to prevent it from melting. The 45 gelatin sheet may freely expand and contract but it is not frangible and will not break. It will remain unchanged and will resist a high degree of heat.

In Fig. 8 a slight modified form of the 50 glare-eliminating panel is shown. In this form the blue gelatin sheet 19 is provided with a sheet of gauze 20^a which is secured to one side thereof by bending the ends of the sheet over the edges of the gelatin sheet 55 and clamping them thereto. The gauze sheet 20^a may be secured in any suitable manner to the gelatine sheet.

What we claim is:

1. The combination with a furnace having 55 a peep-opening, of a panel of transparent glare-eliminating material supported outside of the furnace in line with said opening; a woven wire heat-absorbing sheet located between said panel and the peep opening; an opaque closure panel located inwardly of the heat-absorbing panel and adapted to be shifted into and out of a position to close the peep-opening; and a closure panel of transparent heat-resisting material 60 adapted to be shifted into a position to reg-

ister with the peep-opening inwardly of the heat-absorbing panel when the opaque panel is moved out of its closing position.

2. An observation window for furnaces comprising a casing open at its inner end 70 and formed with an observation opening at its outer end in alignment with the open inner end; a panel of transparent glare-eliminating material extending across said observation opening; a shiftable heat-resisting closure member for the inner end of the casing; a light admitting heat-absorbing sheet mounted within the casing between the closure member and the glare-eliminating panel and adapted to protect said panel from 75 the furnace heat.

3. An observation window for furnaces comprising a casing formed with open inner and outer ends in alinement with each other; a panel of transparent glare-eliminating material closing the outer end of the casing; a shiftable closure for the inner end of the casing; and a metallic heat-absorbing and conducting sheet adapted to admit light, located between the glare-eliminating panel 80 and the said closure, said sheet being adapted to protect said panel from the furnace heat and the casing being formed to admit an outside air current to the heat-absorbing sheet.

4. An observation window for furnaces comprising a casing formed with open inner and outer ends in alinement with each other; a panel of transparent glare-eliminating material closing the outer end of the casing; a shiftable closure for the inner end of the casing; a sheet of woven wire mounted within the casing between the closure and the panel and spaced from both, said sheet being adapted to protect the panel from the furnace heat, and the casing being formed with openings 85 in the top and bottom thereof to admit transverse air currents from the outside across the said sheet.

5. An observation window for furnaces comprising a casing formed with open inner and outer ends in alinement with each other; a panel of transparent glare-eliminating material closing the outer end of the casing; a closure-member slidably connected to the casing to move across the inner end thereof 90 and provided with an opaque heat resisting area; a panel of transparent heat resisting material carried by the closure member, said transparent panel and opaque area being adapted to alternately close the inner end of the casing when the closure member is shifted in opposite directions, and a sheet of woven wire located between the glare-eliminating panel and the closure member 95 and adapted to protect the glare-eliminating panel from the furnace heat, the casing being formed with openings permitting free circulation of outside air across said woven sheet.

6. The combination of a furnace having 100

5 a peep-opening, of a casing attached at its inner end to the furnace at said opening, a panel of transparent glare-eliminating material extending transversely of the casing in the line of vision through the peep-opening, a shield slideable transversely of the casing between said panel and opening and closing communication therebetween, said shield having a panel of heat non-conducting material and a panel of transparent heat-resisting material shiftable alternately between the peep-opening and the glare-eliminating panel, and a woven wire heat-absorbing sheet located within the casing between the 10 shield and the glare-eliminating panel, the said casing having openings in its top and bottom walls on one side of the heat-absorbing sheet.

20 7. The combination of a furnace having a peep-opening, of a casing attached at its inner end to the furnace at said opening, a panel of transparent glare-eliminating material extending transversely of the casing in the line of vision through the peep-opening, and comprising a sheet of non-frangible transparent glare-eliminating material and sheets of wire gauze clamped on opposite sides thereof, a shield slideable transversely of the casing between said panel and opening and closing communication therebetween at all times, said shield having a panel of heat non-conducting material and a panel of transparent heat-resisting material shiftable alternately between the peep-opening 25 and the glare-eliminating panel, and a woven heat-absorbing sheet located within the casing between the shield and the glare-eliminating panel, the said casing having openings in its top and bottom walls on both sides of the heat-absorbing sheet.

30 8. The combination of a furnace having a peep-opening, of a casing attached at its inner end to the furnace at said opening, a panel of transparent glare-eliminating material extending transversely of the casing in the line of vision through the peep-opening, and comprising a sheet of non-frangible flexible transparent glare-eliminating material and sheets of wire gauze clamped on 35 opposite sides thereof, a shiftable shield carried by the casing and adapted to be moved into and out of position between the peep-opening and the glare-eliminating panel.

40 9. The combination of a furnace having a peep-opening, of a casing attached at its inner end to the furnace around said opening, a panel of transparent glare-eliminating material extending transversely of the casing in the line of vision through the peep-opening, and comprising a sheet of non-frangible transparent glare-eliminating material and a sheet of wire gauze clamped thereto and covering substantially the entire area of the glare-eliminating material.

45 10. An observation window for furnaces,

50 comprising a casing formed with an observation opening at its outer end, its inner end being open and in alignment with the observation opening; a panel of transparent glare-eliminating material mounted to close said observation opening; a shiftable closure member for the inner end of the casing; a woven wire heat-absorbing sheet located within the casing between the said closure member and the glare-eliminating panel and adapted to protect said panel from the furnace heat; and resilient means pressing the edges of the heat-absorbing sheet into close contact with the metal of the casing.

55 11. An observation window for furnaces, comprising a casing formed with an observation opening at its outer end, its inner end being open and in alignment with the observation opening; a panel of transparent glare-eliminating material mounted to close said observation opening; a shiftable closure member for the inner end of the casing; a removable woven wire heat-absorbing sheet located within the casing between the said closure member and the glare-eliminating panel and adapted to protect said panel from the furnace heat, and resilient means pressing the edges of the heat-absorbing sheet into close contact with the metal of the casing.

60 12. The combination of a furnace having a peep-opening, of a casing attached at its inner end to the furnace around said opening, a panel of transparent glare-eliminating material extending transversely of the casing in the line of vision through the peep-opening, and comprising a sheet of non-frangible transparent glare-eliminating material and a sheet of wire gauze clamped thereto and covering substantially the entire area of the glare-eliminating material, and a woven wire heat-absorbing sheet located between said panel and the peep-opening.

65 13. An observation window for furnaces, comprising a casing formed with open inner and outer ends in alignment with each other, a panel of transparent glare-eliminating material closing the outer end of said casing, a shiftably mounted opaque closure member of heat-resisting material adapted to be shifted to cover and uncover the inner end of the casing, a sheet of transparent heat-resisting material closing said inner end when the opaque closure member is shifted to its uncovering position, and an intermediate light-admitting heat-diverting sheet mounted within the casing between the said transparent sheet and the glare-eliminating panel and spaced from both, the casing being formed with openings adapted to admit an outside air current across one face of said intermediate sheet.

70 14. An observation window for furnaces, comprising a casing formed with open inner and outer ends in alignment with each other,

- a panel of transparent glare-eliminating material closing the outer end of said casing, a shiftably mounted opaque closure member of heat-resisting material adapted to be shifted to cover and uncover the inner end of the casing, a sheet of transparent heat-resisting material closing said inner end when the opaque closure member is shifted to its uncovering position, and an intermediate light-admitting heat-diverting sheet mounted within the casing between the said transparent sheet and the glare-eliminating panel and spaced from both, the casing being formed with openings adapted to admit outside air currents across both faces of said intermediate sheet.
15. An observation window for furnaces, comprising a casing formed with open inner and outer ends in alignment with each other; a panel of transparent glare-eliminating material closing the outer end of the casing; a closure member slidably connected to the casing to move across the inner end thereof and provided with an opaque heat-resisting area; a panel of transparent heat-resisting material carried by the closure member, said transparent panel and opaque area being adapted to alternately close the inner end of the casing when the closure member is shifted in opposite directions; and a metallic heat-absorbing-and-conducting sheet adapted to admit light, located between the glare-eliminating panel and the said closure, said sheet being adapted to protect said panel from the furnace heat and the casing being formed to admit an outside air current to the heat-absorbing sheet.
20. In testimony whereof we hereunto affix our signatures.
